INHALER

Louis H. Morin, New York, N. Y., assignor, by
mesne assignments, to S. Sternau & Co., Inc.,
New York, N. Y., a corporation of New York

Application December 28, 1933, Serial No. 704,226

7 Claims. (Cl. 128—200)

This invention relates to inhaler devices and the object of the invention is to provide a device of this class in connection with which medicinal or other substances are used as an inhaling agent, such, for example, as germicides, inhaling salts, or the like, which may be fluid or a combination of fluid and solids; a further object being to provide an inhaler device in the form of a tube, with means at one end for detachably and rotatably supporting an inhaling head or nozzle in connection therewith, and further with means at the other end of the tube for coupling a protector casing with the device to guard and protect the same as well as to provide means for supporting the complete device in connection with a pocket or other support; a further object being to provide means whereby the head or nozzle is frictionally retained in a closed position and capable of movement into two different positions for distinct uses, with means on the tube for indicating such uses; a further object being to provide a device of the class described, wherein the inhaling head and the coupling sleeve or cap therefor include, as a unit part thereof, a single tube extending downwardly into the tubular body of the device to a point adjacent the lower end thereof; and with these and other objects in view, the invention consists in a device of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view of the device made according to my invention.

Fig. 2 is an enlarged sectional view of the structure shown in Fig. 1 with a part removed, the section being diagrammatic on the line 2—2 of Fig. 3.

Fig. 3 is a section on the line 3—3 of Fig. 2.

Fig. 4 is a view similar to Fig. 3 showing parts in a different position.

Fig. 5 is a side and sectional view of one end portion of the device, the section being diagrammatic on the line 5—5 of Fig. 4.

Fig. 6 is a view similar to Figs. 3 and 4, showing the parts in another position.

Fig. 7 is a perspective view of the head or nozzle detached.

Fig. 8 is a perspective view of the upper end of the device with the nozzle removed; and,

Fig. 9 is a section on the line 9—9 of Fig. 2.

For the purpose of illustrating one method of carrying my invention into effect, I have shown in the accompanying drawing, an inhaler consisting of a tube or container 10, preferably composed of glass or other suitable material, the upper end of which is open, and the lower end 10a of which is closed as clearly seen in Fig. 2. 10

A coupling sleeve 11 is mounted within and secured to the open end of the tube 10 by a suitable cement, and this sleeve protrudes beyond the end of the tube and is externally threaded as indicated at 12 to receive a detachable closure 15 cap 13, the latter having a skirt portion 14 which overlaps the upper end of the tube 10. The outer surface of the skirt portion of the cap 10 is preferably knurled as indicated at 15 to facilitate attachment and detachment of the cap, as will be apparent. The upper end wall 16 of the cap is reduced to form a shoulder portion 17 and the end wall 16 is provided centrally with an aperture 18 to receive a rivet pin 19 of a head or nozzle 20, the latter being rotatably mounted 25 with respect to the cap, including on its lower surface a pin 21 entering an arc-shaped groove 22 in the end wall 16 to limit the rotary movement of the head 20 in two directions.

A conduit or pipe 23 is secured to the end wall 30 16 and opens outwardly through the upper surface thereof and extends downwardly into the tube or container 10 to a point adjacent the lower closed end 10a thereof, as is indicated in Fig. 2 of the drawing. The end wall 16 is also provided 35 in the construction shown with two conduits or passages 24, 24a which open into the container 10 and outwardly through the upper surface of the end wall 16 and with which the discharge passage 25 of the nozzle or head 20 and/or the 40 air supply passage 26 of said head are adapted to register in the several positions of the head in the distinct uses of the device.

The passage 26 opens outwardly through one side of the head adjacent the lower end thereof 45 as indicated at 26a, whereas the passage 25 has an angular offset 25a to bring the same in radial alignment with the pipe 23 as well as with one of the passages 24, 24a. The head 25 includes at its lower end an annular downwardly directed 50 flange 27, which seats in the groove 17 so as to dispose the outer surface of the head in alignment with the corresponding surface of the cap 13, and the flange portion 27 of the head 25 is also preferably knurled on its outer surface to 55

facilitate the rotation of the head into the several positions of adjustment thereof.

A packing ring or gasket 28 is disposed between the upper surface of the coupling sleeve 11 and the lower surface of the end wall 16 to form a seal preventing the discharge of the fluid or other substance 29 from the container between the sleeve 11 and the cap 13. At 30, I have shown a concavo-convex or cup-shaped spring, which is arranged upon the rivet pin 19 and held in place by the rivet head 19a, the spring being cut out as seen at 30a to span the pipe 23, thus preventing the rotation of said spring when the head or nozzle 20 is rotated. It is also preferred that two apertures 30b be disposed therein in alinement with the apertures 24, 24a to complete the communication from the chamber of the container through said apertures 24, 24a, the spring 30 serving to tensionally support the head 20 upon the cap 13 and at the same time to permit the rotation of said head in the use of the device.

Mounted in the protruding portion of the end wall 16 is a spring actuated ball 31, which is adapted to register with a groove 32 formed on the inner surface of the flange 27 at such point as to frictionally retain the head 20 in its neutral or closed position as seen in Fig. 6 of the drawing when the device is not in use. To indicate this position, an arrow including the word "Close" is arranged on the outer surface of the tube 10 as indicated at 33, note Fig. 1. Another arrow, entitled "Spray" is indicated at 34 with the direction indicated to the right as viewed in Fig. 1, whereas a third arrow entitled "Inhale" shown at 35 indicates a turn to the left.

With this indicating means, if the head 20 is held by the fingers of one hand against rotation and the cap 13 is held by the fingers of the other hand and turned to the right, the parts will assume the position indicated in Fig. 3 and diagrammatically illustrated in Fig. 2, that is to say, with the discharge passage 25 in registering alinement with the pipe 23 and the air passage 26 in alinement with the aperture 24.

It will thus be seen that if the head 20 is placed in the nostril and the user draws inwardly through the nostril, the fluid 29 of the container 10 will be drawn upwardly through the pipe 23 and discharged through the passage 25 in a douche or spray-like manner. It will also be apparent that by turning the cap 13 to the left as indicated by the arrow 35, the parts will be moved into the position shown in Fig. 4 and diagrammatically illustrated in Fig. 5, wherein the passage 25 registers with the aperture 24a and the air passage 26 registers with the pipe 23. In this use of the device, air will be drawn into the device through the pipe 23 downwardly into and through the fluid 29, and this saturated air, or what may be termed vapor, will rise from the fluid and be discharged into the nostril through the passage 25. In the neutral or closed position of the device, that is to say, when the ball 31 is in engagement with the groove 32, the passages 25 and 26 are disposed intermediate and out of registering alinement with the pipe 23 as well as the apertures 24 and 24a as is clearly seen in Fig. 6 of the drawing. At this time, it will be understood that my invention is not necessarily limited to the specific arrangement of ports and apertures herein disclosed, nor to the specific means herein illustrated for controlling and regulating the movement of the head or the degree of rotation thereof.

At the closed end of the tube or container 10 is a guard cap 36 cemented or otherwise secured

thereto and including a dome portion 37 covering and protecting the end 10a of the tube, and also having an externally threaded portion 38 by means of which a guard casing 39 may be detachably coupled with the cap 36, the casing 5 being in threaded engagement with the threaded portion 38 as clearly indicated in Fig. 1 of the drawing.

The casing 39 is preferably in the form of a tube of metal, rubber, celluloid, thermo setting 10 type of phenol condensation resins or any other suitable material and may include a plug 40 at the closed end thereof having a flexible packing or gasket 41 on its inner surface, against which the discharge and contracted end of the head 20 15 is adapted to rest when the casing 39 is mounted in position as seen in Fig. 1 of the drawing. The casing 39 also preferably includes a spring clip 42 of any desired or conventional form, by means of which the complete device may be supported 20 in a pocket or in connection with any other support in the manner of mounting and supporting fountain pens and similar devices.

It will be understood that the tube or container 10 may have arranged therein any desired 25 type of medicinal preparation in the form of a fluid or a combination of solids and fluids, and these ingredients may act as germicides for various kinds and classes of nasal and throat treatment or may be in the form of smelling salts or 30 other ingredients.

It will be understood that the fluid or other contents of the container 10 is inserted therein by removal of the cap 13 together with the head 20 and pipe 23, thus providing a quick and efficient means of refilling the device, and by virtue of the simplicity of the construction of the device and the substantially straight lines thereof, the same becomes very compact for shipment and transportation as well as in use, the outer 40 casing in conjunction with the guard cap forming means for reinforcing and protecting the complete devices, especially when not in use, thus insuring long, durable life with a reasonable amount of care. It will also appear that by 45 virtue of the simplicity of the mechanical parts of the device as well as the manner of operation the entire device becomes substantially fool-proof.

It will be apparent that while I have shown 50 certain details of construction for carrying my invention into effect, I am not necessarily limited to these details and various changes in and modifications of the construction herein shown and described may be made within the scope of 55 the appended claims without departing from the spirit of my invention or sacrificing its advantages.

Having fully described my invention, what I claim as new and desire to secure by Letters 60 Patent, is:

1. A nasal applicator comprising a tubular container having a single interior chamber for fluid medicament or the like, an end wall at one end of said container having separate conduits therethrough, one of said conduits being extended downwardly into the interior of said container below the normal level of fluid contained therein a nozzle head rotatably mounted on said end wall and having a lower side in surface contact therewith, said head having a passage extending from the tip thereof to said lower side and having a second separate passage extending from said lower side to the atmosphere, said head passages being adapted selectively to 75

register with said end wall conduits with said tip passage and said extended conduit in registry in one relative position of said head and end wall and with said second passage in registry with 5 said extended conduit in another relative position of said head and end wall.

2. A nasal applicator comprising a tubular container having a single interior chamber for fluid medicament or the like, an end wall at one 10 end of said container having separate conduits therethrough, one of said conduits being extended downwardly into the interior of said container below the normal level of fluid contained therein, a nozzle head rotatably mounted on said 15 end wall and having a lower side in surface contact therewith, said head having a passage extending from the tip thereof to said lower side and having a second separate passage extending from said lower side to the atmosphere, said 20 head passages being adapted selectively to register with said end wall conduits with said tip passage and said extended conduit in registry in one relative position of said head and end wall and with said second passage in registry with 25 said extended conduit in another relative position of said head and end wall, and means for limiting relative rotation between said head and end wall to movement between said named relative 30 positions.

3. A nasal applicator comprising a tubular container having a single interior chamber for fluid medicament or the like, and end wall at one end of said container having separate conduits therethrough, one of said conduits being extended 35 downwardly into the interior of said container below the normal level of fluid contained therein, a nozzle head rotatably mounted on said end wall and having a lower side in surface contact therewith, spring means constantly holding 40 such contacting surfaces against each other under spring tension, said head having a passage extending from the tip thereof to said lower side and having a second separate passage extending from said lower side to the atmosphere, said head 45 passages being adapted selectively to register with said end wall conduits with said tip passage and said extended conduit in registry in one relative position of said head and end wall and with said second passage in registry with said 50 extended conduit in another relative position of said head and end wall, means for limiting relative rotation between said head and end wall to movement between said named relative positions, and means on the device for indicating the several 55 positions of the head and end wall.

4. A nasal applicator comprising a tubular container having a single interior chamber for fluid medicament or the like, an end wall at one end of said container having separate conduits 60 therethrough, one of said conduits being extended downwardly into the interior of said container below the normal level of fluid contained therein, a nozzle head rotatably mounted on said end wall and having a lower side in surface 65 contact therewith, spring means constantly holding such contacting surfaces against each other under spring tension, said head having a passage extending from the tip thereof to said lower side and having a second separate passage 70 extending from said lower side to the atmosphere, said head passages being adapted selectively to register with said end wall conduits with said tip passage and said extended conduit in registry in one relative position of said head and end wall and with said second passage 75

sage in registry with said extended conduit in another relative position of said head and end wall, and with none of said passages and conduits in registry in an intermediate position, means for limiting relative rotation between said head and end wall to movement between said registry effecting relative position, and detent means for holding said head and end wall in said intermediate position. 5

5. A nasal applicator comprising a tubular 10 container having a single interior chamber for fluid medicament or the like, an end wall at one end of said container having three conduits therethrough, one of said conduits being extended downwardly into the interior of said container below the normal level of the fluid contained therein and the remaining conduits opening into said container above said level, a nozzle head rotatably mounted on said end wall and having a lower side in surface contact therewith, said head having a passage extending from the tip thereof to said lower side and having a second separate passage extending from said lower side to the atmosphere, said head passages being adapted selectively to register with 15 said end wall conduits with said tip passage and said extended conduit in registry while said second passage and one of said remaining conduits are in registry, said head passages also being adapted selectively to register with said 20 end wall conduits with said second passage in registry with said extended conduit while said tip passage registers with the other of said remaining conduits. 25

6. A nasal applicator comprising a tubular 30 container having a single interior chamber for fluid medicament or the like, an end wall at one end of said container having three conduits therethrough, one of said conduits being extended downwardly into the interior of said container below the normal level of the fluid contained therein and the remaining conduits opening into said container above said level, a nozzle head rotatably mounted on said end wall and having a lower side in surface contact therewith, 35 said head having a passage extending from the tip thereof to said lower side and having a second separate passage extending from said lower side to the atmosphere, said head passages being adapted selectively to register with said end 40 wall conduits with said tip passage and said extended conduit in registry while said second passage and one of said remaining conduits are in registry, said head passages also being adapted selectively to register with said end wall 45 conduits with said second passage in registry with said extended conduit while said tip passage registers with the other of said remaining conduits, said end wall having an arcuate groove therein, and a pin extending from said head 50 into said groove, said groove being of sufficient length to limit rotation between said head and end wall to movement between said named alternative registering positions. 55

7. A nasal applicator comprising a container 60 having a single enclosed chamber for fluid medicament, separate conduits communicating with the interior of said chamber, one of said conduits being extended downwardly into the interior of said chamber below the normal level 65 of fluid therein, a nozzle head rotatably mounted on said container and having a dispensing passage and an air vent passage extending therethrough, said dispensing passage being registered with said extended conduit and said 70 75

air vent passage being registered with another of said conduits in one relative position of said head and container whereby fluid is forced through said dispensing passage upon application of suction thereto, and said air vent passage being registered with said extended conduit and said dispensing passage being registered with

another of said conduits in a second relative position of said head and container whereby air is forced through said fluid and thence through said dispensing passage in a vapor-laden state upon application of suction of such dispensing 5 passage.

LOUIS H. MORIN.
